UNITED STATES PATENT OFFICE.

WILLIAM ACKROYD, OF WORTLEY, LEEDS, AND CROSSLEY ANDERSON MONTGOMMERY
BUCKLEY, OF BATLEY, NEAR LEEDS, ENGLAND.

SUPERHEATER FOR STEAM-BOILERS.

No. 894,566.

Specification of Letters Patent.

Patented July 28, 1908.

Application filed March 17, 1908. Serial No. 421,608.

To all whom it may concern:

Be it known that we, WILLIAM ACKROYD, of Wortley, Leeds, and CROSSLEY ANDERSON MONTGOMMERY BUCKLEY, of Batley, near 5 Leeds, both in the county of York, England, and both subjects of the King of Great Britain, have invented a certain new and useful Improved Superheater for Steam-Boilers, and of which the following is a specification.

10 This invention relates to an improved steam superheater, particularly adapted for use in connection with horizontal steam boilers commonly known as Lancashire boilers.

The superheater constructed according to 15 this invention consists of a vertical box-like casing of semi-circular or other convenient shape in plan, said casing being fitted up to the back end of the boiler; and to one end of the casing, at its upper part, is attached a 20 steam pipe from the boiler, while to the other end of the casing, at its upper part, is attached a steam delivery pipe. The casing is divided internally by means of division plates or walls so as to form a series of chambers or compartments which may be of a progressively increasing area from the inlet end 25 of the casing toward its outlet end, which division plates or walls, preferably arranged vertically, are alternately cut short top and bottom of the casing so that the steam is caused to pass down and up each alternate chamber in its course through the casing from the inlet end to the outlet end. Such a 30 box-like casing is arranged at the rear end of the boiler so that its ends abut against the rear end of the said boiler, and so a chamber is formed with which the boiler flues communicate and the products of combustion pass through and into the chamber and find their 35 exit by an under-flue, the top and base of the chamber formed by this box-like casing being closed. We have found that a superheater of this description is economical in construction and very efficient in use.

40 Our invention is described with reference to the accompanying drawings.

Figures 1 and 2 are respectively a sectional side elevation and a part sectional plan, of a "Lancashire" boiler fitted with a 45 steam superheater in accordance with our invention; and Figs. 3 and 4 are respectively a part sectional front elevation and a sectional plan, of the superheater detached and drawn to an enlarged scale.

50 In the drawings, the superheater consists

of a vertical box-like casing 1, of semi-circular shape in plan, fitted up to the back end of the boiler 2 in the manner and in lieu of the usual flue dividing walls; and to one end of the casing 1, at its upper part, is attached a 55 steam pipe 3 from the boiler 2, while to the other end of the casing 1, at its upper part, is attached a steam delivery pipe 4. The casing 1 is divided internally by means of division plates 5 into a series of vertically 60 arranged chambers or compartments 6. The division plates 5 are alternately cut short top and bottom of the casing 1 so that the steam entering by way of the pipe 3 is caused to pass down and up in the alternate chambers 65 6 of the casing 1 in its course to the outlet pipe 4.

It will be seen that in employing the above form of steam superheater, the great heat from the boiler flues 7 is caused to play directly on to and over the entire interior surface of the said superheater, which latter then acts to divert the heat along the central under flue 8 of the boiler; and further, that the heat passing along the side flues 9 of 70 the boiler to the outlet flue 10 is caused to play directly on the exterior surface of the said superheater, whereby the steam passing through the latter is quickly superheated, while a definite circulation of the steam is set 75 80 up by the superheater on account of its particular internal construction.

In case any water should be formed in the superheater, we could make holes at the bases of the division plates 5 within the casing 1 so as to allow the water to drain to one end of the latter, and then conduct the water away from the end of the casing 1 by an outlet coupled up say by means of a pipe to a 85 convenient receptacle or receiver.

90 What we claim as our invention and desire to secure by patent is:—

1. In superheaters for steam boilers; the combination with a steam boiler, a furnace for heating same, and flues for conducting the 100 products of combustion; of a vertical box-like casing located at the rear of said boiler, the vertical ends of said casing abutting upon the rear end of said boiler said casing being shaped in plan to form a chamber between 105 the inner wall of said casing and the rear end of said boiler, into which chamber said flues of said boiler open, vertical division plates located in said casing, one of said division plates not reaching the top of said casing and the 110

next division plate not reaching the bottom of said casing to provide a circuitous path for steam within the said casing, a pipe from said boiler communicating with the top of said casing at one of the ends of said casing abutting upon the rear of the boiler to conduct steam thereto, and a steam delivery pipe communicating with the top of said casing at the opposite end thereof to convey away the 10 superheated steam substantially as set forth.

2. In superheaters for steam boilers; the combination with a steam boiler, a furnace for heating same and flues for conducting the products of combustion; of a vertical box-like casing located at the rear of said boiler, the ends of said casing abutting upon the rear end of said boiler, said casing being shaped in plan to form a chamber between the inner wall of said casing and the rear end 15 of said boiler into which chamber said flues of said boiler enter, vertical division plates located in said casing one of said division plates not reaching to the top of said casing and the next division plate not reaching to 20 the bottom of said casing, a pipe from said boiler communicating with the top of said casing at one end thereof to conduct steam from said boiler thereto, and a steam delivery pipe communicating with the top of said 25 casing at the opposite end thereof to convey away the superheated steam, the distance between said division plates in said casing being less at that end into which the supply pipe enters and progressively increasing in 30 distance apart towards the delivery end of said casing, substantially as set forth.

3. In superheaters for steam boilers; the combination with a horizontal steam boiler, a furnace at the front end of same, boiler 40 flues passing through said boiler and opening at the rear end, a flue passing centrally beneath said boiler from the rear to near the front end, and side flues communicating with said under-central flue; of a vertical box-like casing located at the rear end of said boiler, the vertical ends of said casing abutting upon the rear end of said boiler and said casing being shaped in plan to form a chamber between the inner wall of said casing and the 45 rear end of said boiler, means for closing the upper and lower ends of said chamber, into 50

which latter said boiler flue and said central under-flue open, a steam supply pipe from said boiler communicating with the top of said casing at one end thereof, and a steam 55 delivery pipe communicating with the top of said casing at the opposite end thereof, vertical division plates in said casing to form circuitous passage for the steam within said casing from the supply to the delivery pipes 60 aforesaid, substantially as set forth.

4. In superheaters for steam boilers; the combination with a horizontal steam boiler, a furnace at the front end of same, boiler flues passing through said boiler and opening 65 at the rear end to conduct the products of combustion from said furnace, a flue passing centrally beneath said boiler from the rear end to near the front end thereof, side flues communicating with the forward end of said 70 under-central flue, and an outlet flue with which the forward ends of said side flues communicate; of a vertical box-like casing located at the rear end of said boiler, the vertical ends of said casing abutting upon the 75 rear end of said boiler, said casing being semi-circular in plan to form a chamber between the inner wall of said casing and the rear end of said boiler, means for closing the upper and lower ends of said chamber with 80 which latter the boiler flues and the under-central flue communicate, a steam supply pipe from said boiler communicating with the top of said casing at one end thereof, and a steam delivery pipe communicating with 85 the top of said casing at the opposite end thereof, vertical division plates located in said casing, one of said division plates not reaching to the top of said casing and the next division plate not reaching to the bottom of said casing, the distance between said 90 division plates in said casing being less at that end into which the supply pipe enters and progressively increasing in distance apart towards the delivery end of said casing 95 substantially as set forth.

WILLIAM ACKROYD.
